DESIGN FOR A HANDLE FOR POTS AND PANS

Richard S. Reynolds, Richmond, Va., assignor to
Reynolds Metals Company, Richmond, Va., a
corporation of Delaware

Application July 12, 1945, Serial No. 120,682

Term of patent 14 years

(Cl. D44—29)

To all whom it may concern:

Be it known that I, Richard S. Reynolds, a citizen of the United States, residing at Richmond, Virginia, have invented a new, original, and ornamental Design for a Handle for Pots and Pans, of which the following is a specification, reference being had to the accompanying drawing forming a part thereof.

Fig. 1 is a top plan view of a handle for pots and pans, showing my design;

Fig. 2 is a side elevation of the handle shown in Fig. 1;

Fig. 3 is a bottom plan view of the handle; and

Fig. 4 is a perspective view of the handle embodying my design.

I claim:

The ornamental design for a handle for pots and pans, as shown.

RICHARD S. REYNOLDS.
